UNITED STATES PATENT OFFICE.

MAURICE F. FITZGERALD, OF WINSTED, CONNECTICUT, ASSIGNOR TO THE FITZGERALD MFG. CO., OF TORRINGTON, CONNECTICUT, A CORPORATION OF CONNECTICUT.

AUTOMOBILE-HORN.

1,355,550.

Specification of Letters Patent.

Patented Oct. 12, 1920.

Application filed July 16, 1920. Serial No. 396,711.

To all whom it may concern:

Be it known that I, MAURICE F. FITZGERALD, a citizen of the United States, residing at Winsted, in the county of Litchfield, 5 State of Connecticut, have invented certain new and useful Improvements in Automobile-Horns, of which the following is a description, reference being had to the accompanying drawing and to the figures of reference marked thereon.

This invention relates to automobile horns, and more particularly to means for preventing the objectionable rattling of these horns when the automobile is in motion.

15 In the common types of the present day automobile horn, the vibrations of the sound diaphragm are generally obtained by utilizing the inertia of a rotatable wheel which contacts against the diaphragm. These 20 wheels are actuated by means of a hand reciprocated rack and pinion mechanism, through the intermediary of a pawl and ratchet connection which positively drives the wheel forward, and at the same time, 25 permitting it to freely over-run. In order to secure advantage of the inertia of the wheel, it must be freely mounted on its supporting spindle, and as a result of this free 30 mounting, there is nothing to prevent the wheel from producing the rattling so objectionable to this type of device and to this end, the present invention is directed to provide means for preventing this inertia wheel from rattling during the period when 35 the horn is not being sounded.

A further object of this invention is to provide means automatically controlled by the wheel rotating means for holding the inertia wheel from rattling when it is idle.

40 Still another object of this invention is to construct a horn of the above character in which the means for rotating the inertia wheel also acts to hold the same against rattling movement when normally idle, together with automatic means for bringing the wheel holding means into action at the proper time.

These and other objects will in part be obvious, and will in part be hereinafter 45 more fully disclosed.

Referring more particularly to the accompanying drawings:—

Figure 1 shows a side elevation, partly in section of the device;

55 Fig. 2 is a sectional view on the line 2—2

of Fig. 1 showing the anti-rattling mechanism, and

Fig. 3 is a sectional view on the line 3—3 of Fig. 1 looking in the direction of the arrow.

In general, the invention comprises a diaphragm vibratable by means of the usual notched inertia wheel driven from a rotatable shaft, which shaft in turn is provided with a pinion driven by a hand operated rack. The inertia wheel is loosely mounted on the shaft and is rotated therefrom by means of the usual pawl and ratchet connection so that the wheel can run ahead of the rotating shaft. Means is provided 60 for holding the inertia wheel rigidly from rattling during the inoperative period of the shaft operating means, and one manner of accomplishing this result is secured by splining the ratchet sleeve on the rotatable shaft 65 whereby it may move laterally into and out of contact with the inertia wheel, and there is also provided automatic means for so moving this ratchet sleeve at the proper time. This function is preferably secured 70 by screwthreading that end of the rotatable shaft adjacent the surrounding ratchet sleeve and mounting a nut on said threaded portion, and providing means for holding 75 said nut from rotation so that when the shaft is rotated, the nut will automatically travel away from the ratchet sleeve, thereby freeing the wheel and permitting it to be properly rotated, but when the rotatable shaft is reversely rotated, and the shaft actuating means brought to rest, the nut will 80 travel inwardly along the threaded portion of the shaft, will engage the end of the splined ratchet sleeve, and force the said 85 sleeve inwardly against the inertia wheel, 90 thereby clamping the same from movement and preventing it from rattling.

Referring more particularly to the accompanying drawing, the horn and its casing, indicated at 1 is provided in any suitable manner with a diaphragm 2 vibrated by the usual inertia wheel or actuator 3. As shown clearly in Fig. 2, this inertia wheel is mounted loosely on the shaft 4, freely rotating in bearings 5 and 6 located at diametrically opposite points in the horn casing. In the present construction, to one end of the shaft 4 is fixed a surrounding sleeve 7 provided on its circumference with teeth 8 to form a pinion, which teeth 8 mesh with 100 105 110

the teeth 9 of a rack 10 reciprocable in a sleeve 11 arranged transversely to the shaft 4 and fixed suitably in the walls of the horn casing. This sleeve 11 is suitably cut-away 5 as at 12 to permit the teeth 8 and 9 of the rack and pinion to suitably mesh. In addition, there is provided the usual spring 13 suitably connected to the shaft 4 and to the surrounding casing for returning the plunger 10 to normal outward position after it 10 has been inwardly reciprocated by pressure on the handle 14. In order to drive the inertia wheel from the rotatable shaft 4, there is provided a ratchet sleeve 15 surrounding 15 said shaft 4 and this sleeve 15 is provided with the usual ratchet teeth 16 engaging the usual spring pressed pawls 17, so that when the shaft rotates the ratchet sleeve, it will impel the inertia wheel, which because of 20 the pawl and ratchet construction, can run ahead of the shaft to produce the maximum vibrations.

In consequence of the foregoing construction, this inertia wheel 3 is necessarily 25 loosely mounted on the rotating shaft 4, and due to this mounting, produces a distinct rattling noise due to inherent lateral play. One form of device for overcoming this objectionable rattling, and for holding the inertia wheel positively from movement during 30 the non-rotating period of the driving shafts, is provided by suitably splining the ratchet sleeve 15 on the shaft 4, as by means of the slot 18 in the sleeve 15 and the pin 19 passing transversely through the shaft 4. By 35 means of this construction, the ratchet sleeve 15 can be moved axially of the shaft 4 into and out of clamping contact with the wheel 3.

40 Additional means is provided for automatically producing this axial movement of the sleeve 15, and the preferred form comprises a nut 20 surrounding that end of the shaft 4 adjacent the ratchet sleeve 15 and 45 having threaded engagement with suitable screw threads 21 formed thereon. A yoke 22 shown clearly in Fig. 1 is secured by means of the nut 23 to the horn casing and this yoke is provided with spaced arms 24 50 embracing the nut 20 to hold the same from rotation. As a result of the above construction, when the plunger 10 is reciprocated downwardly, it rotates the pinion 8, sleeve 7 and shaft 4 fixed thereto, which in turn, 55 by means of the splined connections 18 and 19 rotates the ratchet sleeve 15, and through the pawls 17, the inertia wheel 3, which, by means of its peripheral ratchet teeth, vibrates the horn. Upon the initial movement 60 of the rotatable shaft 4 and the threaded surfaces 21 thereon engaging the threads of the nut 20, which is held from rotation by a yoke 24, the nut 20 will immediately move away from contact with the 65 ratchet sleeve 15, thereby permitting the

free movement of the inertia wheel 3. When the plunger 10 has resumed its normal idle position, shown in full lines in Fig. 2, the shaft 4 will be reversely rotated and the nut 20 will consequently travel inwardly into full contact with the ratchet sleeve 15 and press it firmly against the inner face of the inertia wheel 3, thus holding the same from rattling.

70 It is obvious that a device of the above character is not only automatic in its operation, so that the clamping of the inertia wheel from objectionable movement is accomplished, during the non-operating period of the horn, but it is also apparent 80 that there are very few alterations necessary to provide the present type of horn into an anti-rattling device.

Another advantage of the present construction resides in the fact that the ratchet sleeve which constitutes the means for driving the inertia wheel is also part of the means for holding the inertia wheel against rattling movement.

85 It is obvious that minor changes in the details of construction and the arrangement of the parts may be made, without departing from the spirit of the invention as set forth in the appended claims.

90 Having thus described the invention, what I claim as new and desire to secure by Letters-Patent, is—

1. A device of the character described comprising a diaphragm, a rotary actuator therefor, means to rotate said actuator, 100 means to prevent said actuator from rattling, said means coming into operation when said actuator operating means is normally idle.

2. A device of the character described 105 comprising a diaphragm, a rotatable shaft, means to drive the same, an inertia wheel loosely mounted on said shaft, means to drive said wheel from said shaft, and means to hold said wheel from rattling during the 110 idle period of said shaft driving means and to release said wheel for free operation during a portion of the working period of said shaft driving means.

3. A device of the character described 115 comprising a diaphragm, a rotatable shaft, means to rotate said shaft, an inertia wheel mounted on said shaft, means to drive said wheel from said shaft, said means being constructed and arranged to automatically hold 120 said wheel from rattling during the idle period of said shaft driving means.

4. A device of the character described 125 comprising a diaphragm, a rotatable shaft, means to rotate the same, an inertia wheel loose on said shaft but driven therefrom, and means automatically controlled by the shaft actuating means and movable into contact with said wheel to prevent the same from rattling.

5. A device of the character described comprising a diaphragm, a rotatable shaft, means to rotate the same, an inertia wheel loosely mounted on said shaft, means to 5 drive said wheel from said shaft, and means for automatically moving said wheel driving means into and out of clamping contact with said wheel during the idle and actuating periods respectively of said shaft actuating means.
- 10 6. A device of the character described comprising a diaphragm, a rotatable shaft provided with a threaded portion, means to rotate said shaft, an inertia wheel adapted 15 to vibrate said diaphragm, a ratchet sleeve splined on said shaft and movable axially of said shaft into and out of contact with said inertia wheel, pawls connected to said wheel and coöperating with said ratchet sleeve to drive said inertia wheel from said shaft, a nut engaging the threads of said shaft, and means for holding said nut from rotation.
- 20 7. A device of the character described comprising a diaphragm, a rotary actuator therefor, means to rotate said actuator, and means actuated by the operation of the device to prevent said actuator from rattling.

In testimony whereof, I affix my signature.

MAURICE F. FITZGERALD.
